UNITED STATES PATENT OFFICE.

RAYMOND A. DORNES, OF NEW YORK, N. Y.

PUMP.

1,143,255.

Specification of Letters Patent. Patented June 15, 1915.

Application filed August 7, 1912. Serial No. 713,775.

To all whom it may concern:

Be it known that I, RAYMOND A. DORNES, a citizen of the Republic of France, residing in the borough of Manhattan, city, county, and State of New York, have invented certain new and useful Improvements in Pumps, of which the following is a specification.

The object of my invention is to produce 10 a pump of simple construction and high efficiency.

The invention relates to that type of pumps in which a series of propeller blade sections are carried by a shaft, with idler 15 sections interposed between said sections and loosely mounted on said shaft.

One embodiment of my invention is shown in the accompanying drawings in which—

Figure 1 is an elevation of the pump with 20 part of the casing removed. Figs. 2 and 4 are elevations on a larger scale of an idler and propeller blade section respectively. Fig. 3 is an end view of Fig. 4. Fig. 5 is an elevation on a larger scale of a propeller and 25 idler blade section, the latter having a larger pitch than the former.

Referring to the drawings, A designates a shaft which may be driven from any suitable source, held or carried in bearings B B' 30 at the ends of a casing C, which is concentric with the shaft.

D designates a thrust bearing which is preferably constructed with bearing balls.

A cap E is provided which can be screwed 35 into bearing B' to close its end and make it water-tight. Any suitable means may be provided to render bearing B water-tight. The propeller blade sections P are keyed or fastened to the shaft in any convenient 40 way. The idler blade sections I are mounted adjacent to the propeller blade sections and on the delivery side thereof. They are loosely mounted and, hence, are free to turn independently of the shaft as impelled by 45 the oncoming liquid. The pitch of said propeller and idler blades is in the same direction and may or may not have the same value. Each propeller blade section consists of a hub F and a blade or blades 50 G G which have the same radial depth throughout their length. Preferably two blades are used which are set at 180° with respect to each other. The idler sections are or may be identical with the propeller sections except that they may be made longer 55 or shorter in an axial direction as desired.

The action of the pump is as follows: When the shaft is turned the water or other liquid is caught by the first propeller section and given a forward movement, which is accompanied incidentally by a whirling or rotative movement of greater or less velocity. The actual direction of flow at this time is nearly at right angles to the propeller blade. Resolving this motion into its two components, it is seen to consist of a forward or work component and of a rotative or lateral component, which latter is detrimental to the high efficiency of the pump. Were this rotation or whirling motion allowed to continue, the friction of the liquid with the walls of the casing would be increased, eddies or local whirls would be set up, and the second propeller turning in a liquid which is rotating in the same direction as said propeller, would have an extremely low efficiency. To reduce this whirling or rotative motion, with its accompanying friction and eddies, the idler sections are provided which, having a pitch in the same direction as the 75 propeller sections, are caused to rotate in the same direction by this very rotative component, and so tend to prevent liquid passing, unless said liquid is moving in a line parallel to the axis of the shaft. The direction of flow is thus rectified in whole or in part by passing the idler section, and the liquid is delivered to the second propeller moving in more nearly a straight line and freer from eddies, which enables said second 80 propeller to work with greater efficiency than would otherwise be possible. This action is repeated throughout the succeeding stages.

By changing the amount of pitch of the 95 idler with respect to that of the propeller, the speed of rotation of the idler and the amount of the rectifying effect can be varied. Accordingly the best efficiency is thus determinable by trial or experiment. 100

Although, in the above description, I have called my invention a pump, I do not wish to limit it to that function exclusively as it will also operate as a motor.

What I claim is:—

1. A pump comprising a shaft, a propeller blade section mounted fixedly thereon, and an idler blade section mounted loosely thereon, the pitch of said propeller and idler blades having the same direction. 105

2. A pump comprising a shaft, a propeller blade section mounted fixedly thereon 110

and an idler blade section mounted loosely thereon and on the delivery side of such propeller blade section, the pitch of said propeller and idler blades having the same direction.

3. A pump comprising a shaft, a plurality of propeller blade sections mounted fixedly thereon and a plurality of idler blade sections mounted loosely thereon, the pitch of 10 said propeller and idler blades having the same direction.

4. A pump comprising a casing, a shaft,

a propeller blade section mounted fixedly thereon, and an idler blade section mounted loosely thereon; the pitch of said propeller 15 and idler blades having the same direction, and being of different value.

In witness whereof, I have hereunto signed my name in the presence of two subscribing witnesses.

RAYMOND A. DORNES.
